(57) **CLAIM**

The ornamental design for an aerodynamic wheel cover, as shown and described.

DESCRIPTION

FIG. 1 is a front perspective view of the aerodynamic wheel cover;

FIG. 2 is a rear perspective view of the aerodynamic wheel cover of FIG. 1;

FIG. 3 is a front view of the aerodynamic wheel cover of FIG. 1;

FIG. 4 is a top plan view of the aerodynamic wheel cover of FIG. 1;

FIG. 5 is a bottom plan view of the aerodynamic wheel cover of FIG. 1;

FIG. 6 is a left-side elevation of the aerodynamic wheel cover of FIG. 1;

FIG. 7 is a right-side elevation of the aerodynamic wheel cover of FIG. 1; and,

FIG. 8 is a rear view of the aerodynamic wheel cover of FIG. 1.

The broken line showing of the four support brackets, the single large bracket and the attachment means is included for the purpose of illustrating environment and forms no part of the claimed design.
